UNITED STATES PATENT OFFICE.

MORRIS BRENNER, OF NEW HAVEN, CONNECTICUT.

SHOW-STAND.

SPECIFICATION forming part of Letters Patent No. 323,631, dated August 4, 1885.

Application filed July 11, 1884. (No model.)

To all whom it may concern:

Be it known that I, MORRIS BRENNER, of New Haven, in the county of New Haven and State of Connecticut, have invented a new 5 Improvement in Show-Stands; and I do hereby declare the following, when taken in connection with accompanying drawings and the letters of reference marked thereon, to be a full, clear, and exact description of the same, 10 and which said drawings constitute part of this specification, and represent in—

Figure 1, a perspective view; Fig. 2, a transverse section.

This invention relates to a stand for the exhibition of neckties, designed to be used in show-cases. The usual method of exhibiting these articles is in boxes, and where but one or two can be seen, they lying one upon another in the box, such boxes occupy considerable space in the show-case, and in order to exhibit them to customers the whole box must be removed, as those underlying cannot be seen until those above are removed.

The object of my invention is a device which 25 may stand in the show-case and upon which a large number of ties may be exposed to view and within a much less space than the box would occupy containing the same number of ties; and it consists in a frame provided with 30 parallel slats inclined backward and upward, each slat having a series of upwardly projecting hooks, upon which the ties may be hung and so as to expose the knot above the frame, leaving room for the ends to hang below, as 35 more fully hereinafter described.

A A represent two frames, which form the ends of the stand, the upper cross-bar preferably inclined. Between the frames a series of parallel bars, B, extend, connecting the two 40 frames. These bars are also inclined backward from the front, the lower side of the frame being understood to be the front. Upon the upper edge of these bars a series of hooks,

a, are arranged, preferably made from wire, and so as to enter into a loop or some portion 45 of the necktie upon its rear side.

The bars B B may be rigidly fixed to the frames and so that the frames and bars may be handled together as one article and set into a show-case, and so that, if desired, the merchant may remove a stand entire from the show-case; or the standards may be made fast to the floor of the show-case and the bars removable from their respective slots in the frame.

The ties are arranged upon the hooks as 55 seen in Fig. 1, each held by its own independent hook. There being a space between the bars, either of the ties on the frame may be removed by reaching beneath the bars and, taking hold of the particular one required, lift 60 it from its hook, and by a reverse operation it may be readily reset upon its hook or another in its place.

A show-stand of this construction, occupying no more space than would a box for half 65 a dozen ties, will readily support three or four times that number, and expose each and every one in a neat and tasteful manner, as well as permitting their arrangement so that either may be conveniently taken from the stand 70 without interfering with others.

The inclination of the bars forms a base upon which the ties will lie and cause their faces to be turned upward to such an extent as to properly expose them to view. 75

I claim—

A show-stand consisting of the frames A A and bars B B, extending between said frames and supported thereby, the said bars inclined backward and upward and each of said bars 80 provided with a series of hooks, substantially as described.

MORRIS BRENNER.
